UNITED STATES PATENT OFFICE.

FELIX LOUISOT, OF NEW YORK, N. Y., ASSIGNOR TO VACUUM PULP PRODUCTS CORPORATION, OF NEW YORK, N. Y., A COMPANY OF VIRGINIA.

PULP-MOLDING MACHINE.

Application filed July 11, 1923, Serial No. 650,789. Renewed August 16, 1926.

This invention relates to the manufacture of articles from wood pulp or material of a similar nature.

Some of the more important objects of the invention are to simplify the structure, to facilitate and expedite the operation and to increase the capacity and possible output of machines of this character.

The foregoing and other objects are attained in the embodiment of the invention shown in the drawings accompanying and forming part of this specification, but it is to be understood that this illustration is primarily for purposes of disclosure and that the structure may be modified in various respects without departure from the broad spirit of the invention as will be apparent from the scope of the appended claims.

Figure 1 is a side elevation of the machine with the pulp feed tank and certain other parts broken away for lack of space.

Figure 2 is a top plan and partial sectional view of the machine on a somewhat larger scale.

Figure 3 is a broken sectional view taken partly on the longitudinal center line of the machine.

Figure 4 is a fragmentary sectional view of the suction and pressure connection for the movable bottom of the mold chamber.

Figure 5 is a cross sectional view of the machine as taken on substantially the plane of line 5-5 of Figure 1 with one of the molds inside the mold chamber appearing in section.

Figures 6 and 7 are broken sectional detail views of the pulp supply and back wash coupling for the movable mold chamber bottom, illustrating said coupling in both its projected and retracted positions.

Figure 8 is a broken cross sectional view of one of the molds in the mold chamber.

Figure 9 is a perspective detail view of a two part mold constructed to produce an article in the form of a toy rabbit.

Figure 10 is a detail of the product of this mold.

Figure 11 is a broken detail view illustrating the toggle action for closing the mold chamber.

In the illustration 15 designates the mold chamber which is shown as of elongated con-

struction so as to contain a plurality of independent molds, six in number in the present case. This chamber, as best shown in Figure 5, is in the form of an inverted casing having an open lower end closed by a cover or bottom element 16 having an outstanding flange 17 cooperating with the lower edge of the casing to provide an airtight joint. The bottom is shown formed with a raised portion extending well up within the mold chamber to serve in effect as a table for the molds and molded products and this raised portion is spaced inwardly away from the side walls of the chamber to provide a drainage channel 18 in the base of the chamber.

The body of the mold chamber is shown as supported on the upper ends of posts or columns 19 and these columns are utilized as guides for the movable bottom of the mold chamber by providing the bottom with sleeve-like extensions 20 at the opposite ends of the same slidingly fitted over such posts.

To operate the movable bottom, links 21 are shown pivoted at 22 up within the hollow raised portion of the bottom and pivotally connected at their lower ends at 23 with arms 24 carried by shafts 25 journaled in bearing brackets 26 secured on the columns, said shafts being equipped with pinions 27 engaged by gears 28 on shaft 29 which is journaled in the same bearing brackets and is provided with a suitable operating handle 30. It will be evident that by operating this handle the crank arms will be oscillated to raise and lower the bottom and the arms and links are preferably so proportioned and the various centers so disposed that said arms and links will operate as toggles to lock the mold bottom in the closed position. To limit the past-center movement of such toggles the handle carrying shaft may serve as a stop limiting the throw of the crank arms, substantially as indicated in Figure 11.

In large machines the mold chamber bottom may be quite heavy and the same is therefore preferably counter-balanced as by means of counter-balancing weights 31 and 32 at opposite ends of the machine, the first being shown as having a cable 33 extending over a sheave 34 to a lug 35 projecting laterally from one of the guide sleeves and the

other as having a cable 36 extending over guide sheaves 37, 38 to a lug 39 projecting in the opposite direction from the other guide sleeve. The upward pull on the two ends 5 of the table is thus applied at opposite sides of the longitudinal center and this has the effect of balancing the weight and thus overcoming any binding or cramping tendencies. With the construction disclosed the 10 mold chamber can be quickly and easily opened and closed with but little effort and the bottom member will be securely held and locked in closed position.

The molds are shown arranged in a row 15 within the mold chamber and as of two part construction opening toward opposite sides of the chamber. In the present example the molds are given the conformation to produce the toy rabbit shown in Figure 10, and 20 are made in halves 40, 41, separable on a wavy line 42, Figures 5 and 9, at approximately the longitudinal center of the article. The mold walls may be provided by wire 25 gauze or the like, reinforced and carried by suitably shaped frames 43 faced off at their upper and lower ends at 44 and 45 to slidably engage transverse guides 46 in the top of the chamber and the flat screen or perforate support 47 carried by the table. 30 The mold frames are also shown as constructed with hubs or sockets 48 for the plungers or rods 49 by which the mold sections are shifted. The foraminous support 47 is shown as rested on teeth or ridges 50 35 so as to permit free drainage through the same and the mold frames are suitably ribbed so as to expose the foraminous mold wall as much as possible.

The mold rods 49 slide through suitable 40 stuffing boxes 51 in the opposite sides of the mold chamber and are actuated to open up or close all of the molds substantially simultaneously by arms 52 having forked lower ends engaged between collars 53 on the outer 45 ends of the rods, said arms being adjustably clamped at their upper ends at 54 on outwardly projecting studs 55 carried by the bars 56, 57 slidably supported at the opposite sides of the head of the machine by 50 the inwardly projecting slide rods 58 working in transverse bearings 59 on the top of the machine. The slides thus formed are simultaneously shifted in opposite directions by transverse shafts 60, having reversely 55 threaded screws 61, 62 at opposite ends of the same and engaged in screw seats 63, 64 in the ends of the heads 56, 57. For rotating these screw shafts there is shown a shaft 65 extending longitudinally of the machine, 60 having an operating hand wheel 66 conveniently disposed at the same end of the machine where the mold chamber controlling handle 30 is located, said shaft having spiral gears 67 in mesh with interfitting gears 68 on the transverse screw shafts. 65

From this it will be seen that by turning the hand wheel all the molds can be opened and closed substantially simultaneously. The individual adjustment of the dependent shifting arms 52 on their supporting studs 55 70 enables the parts being set to effect the desired results and to handle different shapes and sizes of molds.

The wood pulp or other material in the machine illustrated is fed from a tank 69 75 containing a float actuated valve for maintaining the pulp at a height sufficient to provide a gravity flow into the molds. This tank is connected by piping 70 with a suitable source of supply and is connected by 80 other piping 71 to a special coupling 72 in the side of the mold chamber which is arranged to provide communication with a conduit 73 having branches 74 with vertical 85 risers or branches 75 provided with tubular extensions 76 opening up through the supporting screen 47 on the table directly into the molds.

The coupling 72 is shown in Figures 6 and 7 as comprising a coupling sleeve 77 90 slidably engaged over a tubular neck or extension 78 of the pulp line and rotatably and longitudinally shiftable within a tubular housing 79 in the side of the mold chamber toward and away from the end face 80 95 of the conduit 73. To make a close joint with such conduit the movable coupling sleeve is shown as faced with a rubber or other compressible gasket 81. The shifting and securing of the coupling sleeve is effected by a cam motion including a cam slot 82 cut in the housing 79 and receiving a pin or stud 83 projecting from the sleeve. In Figure 6 the handle 83 is shown as having been turned to advance the same in the cam slot and hence bring the coupling sleeve into close fitting abutting engagement with the lower end of the pulp conduit 73, while in Figure 7 the parts are indicated as they appear when the handle is turned in the reverse direction to retract the sleeve and uncouple it from the conduit. 100 105 110 115

The flow of pulp is controlled by a valve 84 interposed in the pulp line, which may be of the three-way type, arranged in one position to provide a direct flow of pulp from the tank to the molds and adapted in another position to shut off the supply of pulp and open the mold conduit to an exhaust or so-called "backwash" outlet 85. Another valve 86 of the three-way type may be provided in this backwash connection, adapted in normal position to provide an exhaust passage for the backwash and adapted in second position to cut off this outlet and provide communication with a compressed air supply pipe 87, the rate of flow through which may be governed by an interposed hand valve 88. A branch 89 of the compressed air pipe is shown as opening into 120 125 130

the side of the mold chamber and as controlled by a shut off valve 90 and regulating valve 91.

To build up a deposit of material against the mold walls, suction is preferably applied outside the mold, in the present disclosure, by means of a suction conduit 92 under control of a valve 93 connected by a detachable coupling 94 at the side of the mold chamber with a conduit 95 opening into the lower or drainage channel portion of the mold chamber.

The coupling 94 serves as a combined suction and drainage connection and is shown as constructed after the manner of the pulp supply coupling, that is, with a handle 96 operating in a cam slot 97 to shift a slidable coupling sleeve 98 into and out of connection with the end flange 99 of the suction conduit 95. This coupling is shown as carried by a bracket 100 dependent from the side of the mold chamber to bring the coupling to a level low enough to drain the mold chamber.

A branch from the suction line is indicated at 101 opening into the mold chamber by way of a part of the pressure connection 89 and under control of a hand valve 102.

Operation.—With the molds and mold chamber closed as shown in Figures 1, 3, 5, and 8, the usual method of procedure is to first open the pulp valve 84 and fill the molds by gravity. The building up of the first few layers on the mold walls is then initiated by opening up the small suction valve 102 to create a limited suction within the mold chamber, after which the main suction valve 93 is opened to more forcefully build up the deposit and remove some of the excess water. The pulp valve 84 may then be turned to cut off the supply of pulp and release the backwash or excess pulp in the molds. After draining off the backwash the valve 86 may be turned to close off the outlet for the backwash and open up the compressed air supply to the interior of the molds. Then with suction on the outside and pressure on the inside of the molds, the deposit is compacted and solidified and the free moisture removed. A final drain may be effected with the suction shut off and the compressed air on inside the molds, after which the air pressure within the molds may be shut off and the valve 90 opened to admit pressure to the mold chamber outside the molds. This building up of pressure on the outside of the molds tends to loosen the products from the mold walls and to produce a series of distinct loosening shocks, there is usually provided what is known as a flutter valve 103, Figures 2 and 3, in the form of a spring-tensioned valve which will open to atmosphere upon accumulation of a predetermined pressure within the mold chamber. The alternate building up and release of pressure within the mold chamber has the ef-

fect of automatically vibrating or shocking the deposited material free of the mold walls, this operation being controlled by the pressure employed, the closing tension of the flutter valve and the size of the flutter valve as proportioned to the cubic contents of the mold chamber. Preferably, the flutter valve should be of fairly large size and sensitive in operation so as to produce a series of rapidly recurring light impacts.

The molds are opened through operation of the hand wheel 66 and this may be done while the shock pressure is still on so as to automatically effect a separation of the product at the moment the molds are actually opened. The separation of the cooperating mold sections leaves the molded products supported on the screen carried by the table or mold bottom so that with the pressure cut off the mold bottom can then be lowered to expose and deliver the molded products.

As an aid to the most effective operation of the machine, a sight glass 104 may be provided in one end of the mold chamber, giving a lengthwise view of the interior of the chamber and a longitudinally extending window 105 may be provided in one side of the mold chamber which gives a view of all of the several molds. The latter is particularly valuable as enabling the operator to see that all the molds are properly closed or fully opened, also that the molds have the proper sliding fit at top and bottom. This long window also shows whether all the molds are operating equally and if not, enables corrections or adjustments to be made to effect the proper operation of all the molds within the chamber.

What I claim is:

1. In apparatus of the character described, a mold chamber open at its lower end, a pulp supply conduit leading through a side wall of the mold chamber, a movable closure for said open lower end and a sectionalized mold within the mold chamber, the closure having a pulp supply passage extending upwardly into communication with the interior of the mold and having at its lower end a detachable coupling for engagement with the pulp supply conduit enabling free movement of the closure.

2. The structure of claim 1 with parts of the detachable coupling carried by the side of the mold chamber.

3. The structure of claim 1 with the sections of the mold operated by rods extending in through opposite sides of the mold chamber and the mold sections having parts at their upper and lower ends slidably engaging the top of the mold chamber and the closure respectively.

4. The structure of claim 1 with a perforate plate supported by the closure and forming a bottom to the mold.

5. The structure of claim 1 with a suction and drainage passage in the closure provided with a detachable coupling. 70
6. The structure of claim 1 with the detachable coupling including a rotatable and longitudinally slideable coupling sleeve arranged to be advanced and retracted by an inclined cam. 75
- 10 7. The structure of claim 1 with a suction and drainage outlet passage in the closure provided with a detachable coupling and the detachable couplings comprising in each case a rotatable and slideable coupling sleeve arranged to be advanced and retracted by an inclined cam. 80
- 15 8. The structure of claim 1 in which the closure extends upward into the mold chamber and a drainage channel in the bottom of the mold chamber about the lower portion of 85 the closure. 90
- 10 9. The structure of claim 1 with a drainage channel in the bottom of the mold chamber and a suction and drainage conduit opening to said channel and provided with a detachable coupling. 95
- 15 10. The structure of claim 1 in which the closure has a raised central portion providing an elevated table cooperating with the lower end of the mold and an outstanding flange at its lower end for cooperation with dependent side walls of the mold chamber. 100
- 15 11. The structure of claim 1 with a perforate support on the closure cooperating with the bottom of the mold and a tubular extension of the pulp conduit projecting up through said perforate support into the mold chamber. 105
- 15 12. The structure of claim 1 in which the mold chamber has a guide in the top thereof and in which the closure also has a guiding surface, which guides cooperate with the upper and lower ends of the mold sections to guide the same for opening and closing movements. 110
- 15 13. The structure of claim 1 in which the mold chamber has a guide in the top thereof and in which the closure also has a guiding surface, which guides cooperate with the upper and lower ends of the mold sections to guide the same for opening and closing movements, with means extending in through the sides of the mold chamber for operating the mold sections and means for operating the closure. 115
- 15 14. The structure of claim 1 with a toggle mechanism for operating the movable closure and for securing it in closed relation and means for counterbalancing the weight of the movable closure. 120
- 15 15. The structure of claim 1 with the mold chamber supported on upright standards and with the movable closure having guides slidingly engaging said standards. 125
- 15 16. The structure of claim 1 with the mold chamber supported on upright standards and with the movable closure having guides slidingly engaging said standards, lugs projecting from opposite sides of said guides and counterbalancing means connected with said oppositely extending lugs. 70
17. In apparatus of the character described, a mold chamber of greater length than width, a row of separate molds within said elongated chamber, the mold chamber having a movable wall capable of supporting a row of objects produced by said molds, means for operating the molds to leave the molded objects supported on said wall and means for shifting the wall to carry the supported objects clear of the mold chamber. 75
18. In apparatus of the character disclosed, an elongated mold chamber having an open bottom, a movable closure for said bottom, a row of separable molds within the elongated mold chamber, operating connections for said molds entered through the sides of the mold chamber, means for actuating said connections substantially simultaneously and means for operating the closure for the bottom of the mold chamber. 80
19. In apparatus of the character disclosed, a mold chamber having an opening for the discharge of the molded products, a movable closure for said opening, a series of separable molds within the mold chamber, operating rods for the molds entered through opposite sides of the mold chamber, slides carrying arms engaged with said rods and means for simultaneously shifting said slides in opposite directions. 85
20. In apparatus of the character disclosed, a mold chamber having an opening for the discharge of the molded products, a movable closure for said opening, a series of separable molds within the mold chamber, operating rods for the molds entered through opposite sides of the mold chamber, slides carrying arms engaged with said rods, means for simultaneously shifting said slides in opposite directions, including shafts having reversely threaded screws engaged with the slides and an actuating shaft geared to said screw shafts. 90
21. The structure of claim 19 in which independent adjustment is provided at the connecting arms between the slides and rods. 95
22. In apparatus of the character disclosed, a mold chamber, separable molds therein, slides supported on the mold chamber, means for substantially simultaneously shifting said slides in opposite directions and connections from said slides entered through opposite sides of the mold chamber into engagement with the sections of the separable molds. 100
23. In apparatus of the character disclosed, a mold chamber having transverse bearings, slides at opposite sides of the mold chamber supported by certain of said bearings, transverse screw shafts supported by 105
- 130

- other of the bearings and having reversely screw threaded engagement with the respective slides, common means for operating both screw shafts, separable molds in the mold chamber and connections from the slides entered through opposite sides of the mold chamber into engagement with the sections of the separable molds.
24. In apparatus of the character disclosed, upright columns, an inverted mold chamber supported on said columns, a closure for said mold chamber slidably guided by said columns, means for shifting said closure, a separable mold within the mold chamber and means for operating the separable mold.
25. In apparatus of the character disclosed, upright columns, an inverted mold chamber supported on said columns, a closure for said mold chamber slidably guided by said columns, means for shifting said closure, including two sets of toggle arms connected for substantially simultaneous operation by a shaft journaled in brackets mounted on the columns, a separable mold within the mold chamber and means for operating the separable mold.
26. In apparatus of the character disclosed, a mold chamber open at its lower end, a closure for said mold chamber provided with a pulp inlet and below that a suction and drainage outlet open to the interior of the mold chamber and a separable mold within the mold chamber in communication with the pulp inlet.
27. In apparatus of the character disclosed, upright columns, an inverted mold chamber supported on said columns, a closure for said mold chamber slidably guided by said columns, means for shifting said closure, including two sets of toggle arms connected for substantially simultaneous operation by a shaft journaled in brackets mounted on the columns, a separable mold within the mold chamber and means for operating the separable mold, the shaft being positioned to operate as a stop for limiting the movement of the toggles past center.
28. In apparatus of the character disclosed, a mold chamber having a movable closure provided with a pulp inlet in one side thereof with branches extending therefrom up through the top of said closure and separable molds within the mold chamber in communication with the several branches.
29. In apparatus of the character disclosed, a mold chamber having a movable closure provided with a pulp inlet in one side thereof with branches extending therefrom up through the top of said closure and separable molds within the mold chamber in communication with the several branches, said branches having tubular extensions projecting up into the separable molds.
30. The structure of claim 29 with a closed, a mold chamber having a movab-
- perforate support on top of the closure about the tubular extensions and providing a bottom wall for the several molds.
31. In apparatus of the character disclosed, a mold chamber having a movable closure provided with projections, a foraminous support bearing on said projections and separable foraminous molds having one wall provided by said foraminous support.
32. In apparatus of the character disclosed, a mold chamber having a movable closure provided with projections, a foraminous support bearing on said projections, separable foraminous molds having one wall provided by said foraminous support and tubular supply connections extending through the foraminous support into said molds.
33. In apparatus of the character disclosed, a perforate mold having separable sections provided at opposite ends with guides, guiding surfaces slidably engaged by said guides, one of said guiding surfaces being perforate and forming a wall portion of the mold and means for relatively shifting the mold sections for opening and closing the mold.
34. In apparatus of the character disclosed, a mold chamber, a plurality of perforate molds therein, means for filling the same with a moldable material and means for imparting a series of impacts to molded material within the molds for releasing the same from the perforate structure of the molds.
35. In apparatus of the character disclosed, a mold chamber, a perforate mold within said chamber, means for supplying a moldable material to said chamber and rapidly recurring separating impacts to material molded within the perforate molds.
36. In apparatus of the character disclosed, an elongated mold chamber having an elongated movable bottom provided at opposite ends with reversely projecting lateral extensions, counterbalancing means engaged with said extensions and operating means for shifting the bottom, aided by said counterbalancing means.
37. In apparatus of the character disclosed, a mold chamber having a movable bottom provided with a drainage outlet projecting below the side of the mold chamber and a detachable coupling for said outlet carried by and dependent from the side of the mold chamber.
38. In apparatus of the character disclosed, a mold chamber having controllable suction and fluid pressure connections thereto and an automatically operating pressure releasing valve, a perforate mold within the chamber and a pulp supply connection to said perforate mold.
39. In apparatus of the character disclosed, a mold chamber having a movab-

- 6
- wall provided with a conduit and pipe connections for said conduit, including a slidably and rotatably supported coupling sleeve for cooperation with the end of the conduit and a relatively rotatable pin and cam slot for advancing and retracting the sleeve with respect to the conduit.
40. In apparatus of the character disclosed, a mold chamber having a movable wall provided with a conduit, a coupling sleeve for cooperation with the end of said conduit, a housing supporting said sleeve and provided with a cam slot and a handle on the sleeve operating in said slot.
41. In apparatus of the character disclosed, a mold chamber having a movable wall provided with a conduit, a coupling sleeve for cooperation with the end of said conduit, a housing supporting said sleeve and provided with a cam slot and a handle on the sleeve operating in said slot, said housing being carried by a fixed wall of the mold chamber.
42. In apparatus of the character disclosed, a mold chamber having a movable wall provided with a conduit, a coupling sleeve for cooperation with the end of said conduit, a housing supporting said sleeve and provided with a cam slot, a handle on the sleeve operating in said cam slot and a supply pipe having a tubular extension entered within the coupling sleeve.
43. In apparatus of the character disclosed, a mold chamber having a movable wall provided with a conduit, a coupling
- sleeve for cooperation with the end of said conduit, a housing supporting said sleeve and provided with a cam slot and a handle on the sleeve operating in said cam slot, the sleeve operating in said cam slot, the sleeve having at its end a gasket for establishing close fitting connection with the end of the conduit.
44. In apparatus of the character disclosed, an elongated mold chamber, a row of perforate molds within said elongated chamber and a window in one side of the elongated chamber exposing the entire series of molds.
45. In apparatus of the character disclosed, a mold chamber, a separable mold therein, means for creating pressure within the mold chamber to separate an article within the mold from the confining mold walls and means for opening the mold while said separating pressure is operative.
46. The process of molding which includes charging a perforate mold with moldable material, applying pressure to the exterior of said perforate mold to separate the molded article from the confining mold walls and opening the mold while the separating pressure is effective.
47. The process of molding which includes charging a perforate mold with moldable material, applying impacts of separating pressure to the exterior of the perforate mold and opening the mold during continuation of such separating impacts.
- In testimony whereof I affix my signature.
- FELIX LOUISOT.
